J. KENNEDY.

BOLT ANCHOR.

APPLICATION FILED APR. 3, 1920.

Patented Mar. 21, 1922.

Fig. 1.

Inventor
Joseph Kennedy
By his Attorney
E. W. Marshall

UNITED STATES PATENT OFFICE.

JOSEPH KENNEDY, OF NEW YORK, N. Y., ASSIGNOR TO JOHN EDWARD OGDEN, OF MOUNTAINVILLE, NEW YORK.

BOLT ANCHOR.

1,410,259.

Specification of Letters Patent. Patented Mar. 21, 1922.

Original application filed March 29, 1919, Serial No. 286,126. Divided and this application filed April 3, 1920. Serial No. 370,952.

To all whom it may concern:

Be it known that I, JOSEPH KENNEDY, a citizen of the United States, and a resident of New York city, county and State of New York, have invented certain new and useful Improvements in Bolt Anchors, of which the following is a specification, reference being had to the accompanying drawings.

My invention relates to improvements in 10 expansion shields which are designed to be used for bolt anchorages and to a new and useful method of making such shields of sheet metal.

The object of this invention is to provide 15 a simple and inexpensive device which may be effectively used to hold a bolt or screw in material such as brick, stone or cement, with which the threaded device cannot obtain a secure hold directly.

20 Another object is to provide a simple and inexpensive method of making such expansion shields.

In order that the invention may be thoroughly understood, I will now proceed to 25 describe the same in the following specification and will then point out the novel features thereof in appended claims.

This application is a division of application, Serial No. 286,126, filed by me March 30 27th, 1919, which was a continuation in part of co-pending applications which matured May 29th, 1919 as Patents Nos. 1,304,885, 1,304,886 and 1,304,887.

Referring to the drawings:

35 Figure 1 is a plan view of a blank of sheet metal showing its form before it is bent, from which an expansion shield which embodies this invention may be made. This blank is perforated in a manner which provides for the projecting flanges being notched 40 in the manner suggested on page 2, line 21 of the aforesaid Patent #1,304,885.

Figure 2 is an elevation of an expansion shield made from a blank like that shown in 45 Figure 1.

Figure 3 is a bottom plan view of the device shown in Figure 2; and

Figure 4 is a top plan view of the same device.

Like reference characters designate corresponding parts in all of the figures.

50 is an undivided blank of sheet metal of arcuate form. This is provided with a plurality of indentations 51 at its edges and a plurality of perforations 52 on lines F—F, 55 G—G, H—H, I—I, J—J, K—K and L—L, which diverge or lie in a fan-like relation. These perforations may increase in width toward the wider end of the blank along some such lines as thus indicated by the 60 broken lines f—f.

The perforations on the lines G—G, I—I and K—K lie on transverse spiral lines such as M—M which pass through the center of two of the notches 51 on the edges of the 65 blank. The perforations on the lines F—F, H—H, J—J and L—L lie on spiral lines such as N—N which are intermediate those of the perforations previously pointed out.

In forming the shield the edges of the 70 blank 50 are bent inwardly and the metal of the blank near the lines G—G, I—I and K—K is pinched together on the same side. The metal of the blank near the lines F—F, 75 H—H, J—J and L—L is pinched together in the opposite direction. The metal thus pinched together forms multi-ply tapered ribs projecting from opposite sides of the blank. A greater amount of the metal near the wider end of the blank is thus pinched 80 together than near the narrower end of the blank, in order to form the desired taper. In fact, the excess of metal thus pinched together near the wider end of the blank is sufficient to contract this lower 85 edge of the blank to make it shorter than the upper edge.

After these ribs have been formed and the edges of the blank bent as described, the tube is completed by folding the metal 90 about a central axis to form a shield such as 55 in Figures 2, 3 and 4.

The construction is such that the outwardly projecting ribs will have a plurality of teeth 53 and the inwardly projecting 95 ribs will have a plurality of teeth 54. The teeth 54 are preferably so arranged that they lie in a helix of the same pitch as

that of the screw which is to be used with the shield, so that the teeth of the screw will readily engage with them. The teeth 53 will lie in a helix of the same pitch, but 5 will be between the teeth 54 on the inwardly projecting ribs.

The structure thus described is a tapered tube having both inward and outward ribs which progressively increase in height from 10 the larger to the smaller end of the tube. The tube, however, may be cylindrical with tapered inner and outer ribs, or if preferred, either the inner or the outer ribs may be tapered and not the others. It is 15 also entirely within the scope of this invention to provide either inwardly projecting or outwardly projecting ribs. It is, however, desirable to make the tube of a blank of the general arcuate form shown, in order 20 to provide an excess of metal at the inner end of the tube and to provide a tapered bore either of the shell of the tube or of such toothed inner ribs as thus described, in order to provide for the expansion of the 25 device when a bolt is screwed into it. It is only necessary that this taper be formed at some time before the bolt is to be inserted and this taper may be formed by driving the shield into a cylindrical hole prepared 30 for it, which act will contract the inner end of the shield, if it has not been previously constructed with the tapered bore.

What I claim is:

1. An expansion shield of sheet metal 35 with parts of the metal folded to form multi-ply ribs, and folded transversely into a tube having edges of the metal extending from one end to the other thereof, the parts which are thus folded being first cut away 40 to form spaced perforations.

2. An expansion shield of sheet metal with parts thereof bent to form longitudinal indentations, and folded transversely into a tube having edges of the metal extending 45 from one end to the other thereof, the parts which are thus bent being first cut away to form spaced perforations.

3. An expansion shield of sheet metal with parts thereof bent to form longitudinal 50 indentations, and folded transversely into a tube having edges of the metal extending from one end to the other thereof, the parts which are thus bent being first cut away to form spaced perforations on transverse 55 lines so inclined as to lie in a helix in the finished tube.

4. An expansion shield of sheet metal with parts of the metal folded to form multi-ply ribs and other parts bent to form indentations substantially parallel with said ribs, and folded transversely into a tube having 60 edges of the metal extending from one end to the other thereof, the parts which are thus folded and the parts which are

thus being bent first cut away to form 65 tapered perforations.

5. An expansion shield formed from a blank of sheet metal having a smaller transverse dimension near one end than at other parts thereof, with parts of the metal folded 70 to form tapered multi-ply ribs, other parts of the metal bent to form tapered indentations substantially parallel with said ribs, and folded transversely into a tube having edges of the metal extending from one end to the other thereof, the parts which are thus folded and the parts which are thus bent being first cut away to form spaced 75 perforations on transverse lines so inclined as to lie in helices in the finished tube. 80

6. An expansion shield formed from a blank of sheet metal having a smaller transverse dimension near one end than at other parts thereof, with parts of the metal folded 85 to form tapered multi-ply ribs, other parts of the metal bent to form tapered indentations substantially parallel with said ribs, and folded transversely into a tube having edges of the metal extending from one end to the other thereof, the parts which are thus folded and the parts which are thus bent being first cut away to form spaced 90 perforations on transverse lines so inclined as to lie in helices in the finished tube with the helix of the perforations in the ribs 95 spaced from the helix of the perforations in the indentations.

7. The herein described method of making an expansion shield which consists of cutting out a sheet metal blank having 100 flaring sides, cutting said blank to form spaced perforations, making longitudinally disposed bends in the perforated parts of the blank to bring said sides substantially parallel, and folding said blank transversely 105 into a tube.

8. An expansion shield of sheet metal with parts of the metal folded to form tapered multi-ply ribs, and folded transversely into a tube having edges of the metal extending 110 from one end to the other thereof, the parts which are thus folded being first cut away to form spaced perforations.

9. An expansion shield of sheet metal with parts thereof bent to form longitudinal 115 tapered indentations, and folded transversely into a tube having edges of the metal extending from one end to the other thereof, the parts which are thus bent being first cut away to form spaced perforations. 120

10. An expansion shield formed from a blank of sheet metal having a smaller transverse dimension at one end than at the other end thereof, with parts of the metal folded to form tapered multi-ply ribs and other parts bent to form indentations substantially parallel with said ribs, and folded transversely into a tapered tube having 125

edges of the metal extending from one end to the other thereof, the parts which are thus folded and the parts which are thus bent being first cut away to form tapered 5 perforations.

11. An expansion shield of sheet metal with parts of the metal folded to form ribs of a plurality of thicknesses, the parts which are thus folded being cut away to form

spaced perforations, and the metal being 10 bent about a longitudinal axis with edges of the metal extending from one end of the shield to the other.

In witness whereof, I have hereunto set my hand this 31st day of March, 1920.

JOSEPH KENNEDY.

Witness:

I. B. MOORE.
